(57) CLAIM

An ornamental design for a hospital gown, substantially as shown in the drawings.

DESCRIPTION

FIG. 1 is an elevation view of the front, left panel in open position of the hospital gown showing our new design.

FIG. 2 is an elevation view of the front, right panel in open position, left panel in partially open position of the hospital gown showing our new design; and,

FIG. 3 is an elevation view of the front, both panels in open position of the hospital gown showing our new design.

The broken lines are for illustrative purposes only and form no part of the claimed design.
